UNITED STATES PATENT OFFICE.

WILLIAM SAUNDERS, OF OAKLAND, CALIFORNIA.

LOOSE-LEAF BINDER.

SPECIFICATION forming part of Letters Patent No. 733,599, dated July 14, 1903.

Application filed September 10, 1901. Serial No. 74,980. (No model.)

To all whom it may concern:

Be it known that I, WILLIAM SAUNDERS, a citizen of the United States, residing at 1505 Brush street, Oakland, in the county of Alameda and State of California, have invented certain new and useful Improvements in Loose-Leaf Binders; and I do hereby declare the following to be a full, clear, and exact description of said invention, such as will enable others skilled in the art to which it most nearly appertains to make, use, and practice the same.

This invention relates to improvements in "loose-leaf binders," and particularly to loose-leaf ledgers.

15 The object of this invention is to produce a simple, cheap, and efficient binding easily manipulated and neat in appearance.

In the drawings, Figure 1 is an isometrical plan of the open backs and binding, the leaves 20 of the book being omitted. Fig. 2 is a side elevation of the same. Fig. 3 is a side elevation of the complete book in closed position. Fig. 4 is an end elevation of the hardware used in the construction of the binder minus 25 the leaves and backs. Fig. 5 is a plan view of the independent binding-bar. Fig. 6 is an isometrical perspective of the binding-post used in the type of expansive binding, showing method of attachment to backs.

30 In the description with reference to the drawings the letter A will be used to designate the side binding-posts; B, the base therefor, attached to the back C; D, the binding-bar, secured to the back C; E, the independent binding-bar.

In construction the invention consists of the back C, to which the stiff sides C' are hinged. Between the hinges of the sides and the semiflexible back a narrow strip of metal 40 C² and C³ is inserted under the leather of the back adjacent to the hinges of the sides. Screwed or riveted to the strip C² on the one side is the binding-strip B, to which are secured the binding-posts A, permanently (see 45 Fig. 1) or detachably. (See Fig. 6.) The posts A consist of upright members, corresponding in width to B, in connection with which they encircle the leaves of the book on three sides. The leaves are notched half-round on each side near the head or binding end to coincide with and engage the half-rounds A', secured to the inside of the posts

A. This holds the leaves in positive alinement with each other and the binding. Extending between the posts is the independent binding-bar E, consisting of a strip of metal notched half-round at each end to engage the half-rounds A', with which it is locked by the fixed pin E', and the latch-pin E², engaging coincident perforations A² in the binding-posts. In this manner the leaves are securely bound together and attached to the back C. 55

Secured to the strip C³ is the binding-strip D. When the book is closed, (see Fig. 3,) this strip D lies over the bar E, the perforations D' engaging the pins A³, swivels D² engaging the slot A⁴ in the offset extensions A⁵ of the binding-posts in such a manner that when the swivels D² are turned partially around a completely-bound volume is formed 60 with the same general appearance and characteristics as any permanently-bound volume. 65

It is obvious that the independent binding-bar E may be dispensed with, it being more of a convenience than a necessity in the binding and removing of leaves. 70

Operation: The book is loaded to capacity with blank leaves. As each is filled it is removed and substituted by a blank. In this manner the book always contains its given 75 number. To remove a leaf from the body of the book, the swivel-locks D² are released, the side and back thrown back, (see Fig. 2,) the pin E² released, and the bar E removed. The leaves lying on top of the one to be removed 80 can be rolled back upon themselves from the top and the leaf withdrawn. In this manner the leaves are disengaged from one binding-post only and the alinement preserved. 85

When it is desired to convert this into an 90 expansive binder, the back C can be made telescoping or dispensed with entirely and the posts A can be provided in varying heights, attachable to B, as shown in Fig. 6, the extension A⁶ of the binding-post engaging the 95 socket B' on the binding-strip B. Thus a book may be started with, say, two hundred and fifty leaves, the height of the posts A being increased as the pages increase, any discrepancy being filled with dummies to preserve 100 the requisite pressure.

Inasmuch as no tools are required in the manipulation of this binder, rapid changes may be made by unskilled persons, which renders

it particularly adapted to ledgers, price-lists, catalogues, &c.

Having thus described this invention, what I claim, and desire to secure by Letters Patent, is—

1. In a loose-leaf binder, the combination with the sides or covers of the binder, of binding-posts located on one of said sides or covers outside the edges of the leaves and adapted to take into notches in the edges of the leaves, and lateral extensions having slots extending inwardly from their edges, of swiveled fasteners on the other cover or side adapted for reception in the slots aforesaid and to lock with the extensions.
2. In a loose-leaf binder, the combination with the sides or covers of the binder, of plates secured to the respective covers and extend-

ing transversely thereof, binding-posts arising from the end portions of one of the plates and assuming the form of rounded pillars on their inner sides and there adapted to take into notches in the edges of the leaves, and outwardly-extending extensions on the posts which are provided with slots made inward from their outer edges, and swiveled fasteners on the other plate at the ends thereof which are adapted for reception in the slots of the extensions to lock the binder.

In testimony whereof I have hereunto set my hand this 26th day of August, 1901.

WILLIAM SAUNDERS.
